ATTORNEYS.

UNITED STATES PATENT OFFICE.

CARL RUTTMANN, OF JERSEY CITY, NEW JERSEY.

WATCH-REGULATOR.

SPECIFICATION forming part of Letters Patent No. 289,359, dated November 27, 1883.

Application filed May 19, 1883. (Model.)

To all whom it may concern:

Be it known that I, CARL RUTTMANN, of Jersey City, in the county of Hudson and State of New Jersey, have invented certain new and useful Improvements in Regulators for Watches, of which the following is a specification.

This invention has reference to an improved regulator for watches which can be set easily and accurately to such a degree of nicety that 10 the watch will indicate the time correctly as to seconds even.

The watch-regulators heretofore in general use cannot be adjusted to that degree of nicety by unskilled hands which is required for regulating the proper running of the watch. Regulators of complicated construction have been devised heretofore, but, besides being more expensive, they cannot be adjusted by the layman, as they require proper implements to set 20 the same.

My improved regulator is adapted to be set accurately without extra tools by any one, so that the watch can be regulated and adjusted, even for small differences in time, without any 25 difficulty; and the invention consists in applying to the longer arm of the regulator a pivoted and slotted lever that is guided along a stop-pin of the arm and provided at its outer end with a fork that engages either an auxiliary 30 regulator-arm or a guided and arc-shaped slide-piece, whereby the regulator is set by a greater or less stroke of the lever more or less to one side or other of the regulator, as required.

35 In the accompanying drawings, Figure 1 represents a plan of my improved regulator for watches. Fig. 2 is a vertical transverse section on line $x-x$, Fig. 1. Fig. 3 is a detail of the lower split arm of the regulator. Figs. 4, 5, and 6 are respectively a plan, a vertical transverse section on line $y-y$, Fig. 4, and a detail of the main arm of a regulator of a modified construction of my regulator. Figs. 8, 9, and 10 are details of another modification.

45 Similar letters of reference indicate corresponding parts.

A represents a regulator-lever which turns in the usual manner by a ring-shaped portion, a , on a fixed disk of the bridge B. The regulator-lever A has a short arm, a' , at one side of the ring-guide a , which arm a' carries pins

that engage the hair-spring, and at the other side a longer arm or index, b . The longer arm b of the regulator A carries a lever, C, that is pivoted at d to the arm b , and guided by a recess or slot, e , along a fixed stop-pin, e' , of the arm b , said recess or slot admitting the lever C to be thrown on its pivot to one side or the other of the axis of the arm b . The outer end of the lever C beyond the pivot d is 60 made fork-shaped or recessed and adapted to engage a fixed pin, f , of an auxiliary arm, D, that is arranged immediately below the regulator-lever A, as shown clearly in Figs. 1 and 2. When the lever C is thrown to one side or 65 to the other, the regulator-lever A will be shifted for a short distance to the same side in proportion to the lateral motion of the lever C.

In place of the lower auxiliary arm, D, an arc-shaped slide-piece, D', may be used, which 70 is guided in an arc-shaped slot, g , of the bridge B, said slot being concentric to the pivot of the regulator-lever A. The slide-piece D' carries the pin f , that is engaged by the forked end of the lever C. By moving the lever C to 75 one side or the other, the regulator-lever A is shifted in the same direction as the lever C, the slide-piece D', like the auxiliary arm D, serving to form a support for the pin f , by which the regulator-lever A is shifted in proportion to the throw of the adjusting-lever C.

In place of the pivot d , the lever C may be guided with a disk-shaped portion, d' , in a circular opening of the regulator-arm b , as shown in Fig. 7, the pin f of the slide-piece D' passing in this case through an opening of the arm b , so as to be engaged by the recessed end of the lever C. When it is desired to regulate the watch so as to overcome a considerable difference in time, the regulator-arm is moved 90 in the usual manner in one or the opposite direction, as the case may be; but when the watch is to be regulated for smaller differences of time, so as to indicate the time correctly as to minutes and seconds, then the lever C is moved 95 to that side to which the regulator-arm is to be set, whereby the latter is moved for a very small distance only, as the lever C throws the regulator-arm b to one side of a line that is drawn through the stop-pin and pin of the auxiliary arm D or slide-piece D'.

By this means a very simple and accurate-

ly-working regulating mechanism is obtained, by which watches may be regulated with great facility, so as to indicate the time with great accuracy.

5 Having thus described my invention, I claim as new and desire to secure by Letters Patent—

1. The combination of the regulator-bridge, a regulator-lever pivoted thereto, an adjusting-lever fulcrumed to the regulator-lever and provided with a forked or recessed outer end, and an auxiliary arm or slide-piece having a fixed pin that is engaged by the forked end of the adjusting-lever, so as to shift the regulator-lever to the same and in proportion to the motion of the adjusting-lever, substantially as set forth.

15 2. The combination of a bridge, a regulator-

lever pivoted thereto, an adjusting-lever fulcrumed to the regulator-lever, means for stopping the adjusting-lever when thrown to either side, and an auxiliary arm or slide-piece carrying a fixed pin, the adjusting-lever being adapted to engage said pin and cause the shifting of the regulator-lever when the adjusting-lever is moved to one side or the other of the axis of the regulator-lever, substantially as set forth.

In testimony that I claim the foregoing as my invention I have signed my name in presence of two subscribing witnesses.

CARL RUTTMANN.
